SLIDE CONTAINER

Joseph W. Rigney, Mesilla Park, N. Mex.

Application March 21, 1951, Serial No. 216,755

2 Claims. (Cl. 129--16)

1

This invention relates to a novel construction of container, receptacle or box for projection slides and has for its primary object to provide a container which may be employed efficiently in the dark or semidarkness for removing projection slides therefrom in series and for returning the projection slides to the container so that the slides will remain in proper series.

More particularly, it is an aim of the present invention to provide a novel construction of container and separator whereby a relatively wide gap will be maintained in a series of slides between the slides of the series which have been projected and those remaining to be projected so that the operator will have no difficulty in locating in the darkness the next slide to be removed from the container and likewise no difficulty in correctly returning the used slide to the container so that the slide will resume its proper sequence in its proper series.

Another object of the invention is to provide a slide container having separating means of extremely simple construction which will move automatically from end-to-end of the container as the slides are removed therefrom and replaced therein and as the number of used slides increases and the number of slides still to be projected decreases.

A further object of the invention is to provide a container of extremely simple construction which may be very economically manufactured and sold and which will afford a smooth interior surface permitting the slides to be applied and removed with ease and without danger of damage thereto.

Numerous other objects and advantages of the invention will hereinafter become more fully apparent from the following description of the drawing, illustrating a presently preferred embodiment thereof, and wherein:

Figure 1 is a plan view of the slide container;

Figure 2 is a longitudinal sectional view thereof taken substantially along a plane as indicated by the line 2--2 of Figure 1;

Figure 3 is a perspective view of the container with the slides and other parts removed therefrom;

Figure 4 is a perspective view of the adjustable stop or follower, and

Figure 5 is a perspective view of the separator.

Referring more specifically to the drawing, the novel slide container constituting the invention is designated generally 7 and includes a rectangular open top box or receptacle, designated generally 8 which may be of any desired length. The end walls 9 and 10 of the receptacle 8 are identical in construction and are each provided

2

with a downwardly and inwardly inclined inner face or surface 11. The receptacle 8 is shown as being provided with a centrally disposed longitudinally extending partition 12 which is equally spaced from opposite sides thereof and the ends of which are anchored in grooves 13 formed in the surfaces 11 of the end walls 9 and 10 whereby the receptacle or box 8 is divided into two corresponding compartments 14 and 15 each of which extends from end-to-end thereof and has corresponding inclined end surfaces 11. The compartments 14 and 15 are each of a width to conveniently accommodate projection slides 16 of a conventional width and may obviously vary in width to accommodate different conventional sizes of projection slides. As previously stated, the box or receptacle 8 may be of any desired length and accordingly the compartments 14 and 15 may likewise be of any desired length. Likewise, the box or receptacle 8 may be of any desired width and may, for example, include only one compartment 14 or 15 in which case the partition 12 is eliminated or may be provided with two or more partitions 12 to form three or more compartments 14 or 15.

The depths of the compartments 14 and 15 are preferably less than the height of a slide 16 from the bottom to the top edges thereof so that even when the slides 16 are in normal, inclined positions, as seen in Figure 2, the upper edges of the slides will preferably project above the level of the open top of the receptacle 8.

One or more series of slides 16 may be stored in each compartment 14 and 15 or all slides of a series may fill a compartment 14 or 15. Where slides of more than one series are contained in a compartment, indicator cards are employed between the series of slides, as illustrated at 17, the indicator cards each being preferably of the same width as the slides but of a greater height so that the upper portion of the indicator cards will extend above the upper edges of the slides. The exposed upper portions of the indicator cards may be provided with suitable indicia designating or descriptive of the series of slides behind or in front of which it is disposed.

Where there are an insufficient number of slides 16 to fill a compartment, an adjustable stop, designated generally 18, is employed in such compartment between the slides 16 thereof and the end wall 10, assuming that the end wall 9 is employed as the front wall of the box. The stop 18 may be of any suitable construction so long as it is provided with an inclined wall surface 19 which is disposed at approximately the same angle as the surfaces 11 and substantially parallel to the surface 11 of the end wall 10. The

stop 18 is shown as being formed of sheet metal having substantially triangular shaped end walls 20 the bottom edges of which are disposed in the same plane as the bottom edge of the inclined wall 19 so that said bottom edges rest upon the bottom 21 of the compartment in which the stop 18 is disposed. The downwardly and rearwardly inclined rear edges of the end walls 20 are preferably provided with inturned flanges 22 for reinforcing said end walls. The stop 18 is preferably of a length substantially equal to the width of the compartments 14 and 15 and its end walls 20 preferably are disposed in slightly diverging relationship to one another from the inclined wall 19 and have sufficient resiliency to frictionally engage against the inner surfaces of the side walls of the compartment in which the stop is disposed to frictionally retain the stop in adjusted positions and so that the slides contained within said compartment will be properly held in an inclined, stacked relationship as illustrated in Figure 2.

The slide container 7 also includes separators 23 each in the form of a roller of a length less than the width of the compartments so that it is capable of rolling longitudinally of the compartment and rests upon the bottom 21 thereof. Each compartment is provided with a roller 23 which when disposed between groups of the slides contained within the compartment will cause the slides on opposite sides of the roller to be inclined upwardly in opposite directions.

Assuming that it is desired to project a series of slides 16, which series begin at the front end of one of the compartments 14 or 15, or adjacent the wall 9, all of the slides are initially disposed at a corresponding incline so as to rest against the surface 11 of the rear wall 10 or the wall 19 of the stop 18, in which position all of the slides 16, will be at an incline corresponding to the slides to the left of the separators 23 as seen in Figures 1 and 2. One of the separators 23 is then inserted between the front wall 9 and the slide 16, adjacent thereto, there being sufficient space in the compartment so that the separator, or roller 23, can rest on the bottom 21 of said compartment. It will then be readily apparent that a substantial gap of substantially V-shape will exist between the surface 11 of the end wall 9 and the adjacent slide 16, so that an operator in the dark may readily place his fingers into this space and remove the slide 16 which is bearing against and immediately to the left of the separator 23, as seen in Figures 1 and 2. After this slide 16 has been projected it is replaced to the right of the roller or separator 23 and between the surface 11 of the wall 9 and said separator and the next slide 16 to the left of the separator 23 is then removed and projected in a like manner. The second slide 16 is then inserted between the separator 23 and the slides to the right of the separator so that as the slides are removed from the receptacle 8, projected and thereafter re-applied thereto, as previously described, the slides will always be returned to the compartment 14 or 15 in their proper sequence. It will likewise be readily apparent that the roller or separator 23 will freely roll along the bottom 21 as the slides are removed and re-applied thus always affording a space to the right of the separator for the next slide to be replaced and which is provided by the slide having been previously removed from the left of the separator. It will likewise be apparent that the separators 23 by being circular in cross section will

permit the slides to be readily applied and removed without damage thereto. It will likewise be apparent that additional indicator cards 17 may be inserted so that selected slides of other series may be readily located to be shown in connection with a series of slides of a different series.

Various modifications and changes are contemplated and may obviously be resorted to, without departing from the spirit or scope of the invention as hereinafter defined by the appended claims.

I claim as my invention:

1. A container for projection slides or the like comprising an elongated open top receptacle having end walls provided with downwardly and inwardly inclined inner surfaces and a substantially flat bottom extending between said end walls, a plurality of projection slides contained within the receptacle each disposed transversely thereof, said slides resting on edge on the bottom and being supported in inclined positions against one or both inclined end wall surfaces, and a roller constituting a separator of a length less than the width of the interior of the receptacle disposed therein transversely thereof and resting upon the receptacle bottom, the slides located on opposite sides of said roller being inclined in opposite directions to define an upwardly diverging gap between the slides located adjacent to and in contact with the roller whereby the slides on one side of the roller may be consecutively removed from the receptacle and replaced therein, after being projected, between the roller and the next adjacent slide on the opposite side of the roller for maintaining the slides in sequence, said roller rolling freely along the receptacle bottom as the slides are removed from one side of the roller and applied to the receptacle on the other side thereof.

2. A filing container comprising an elongated open top receptacle defining a chamber, a plurality of card-like elements disposed in said chamber, said receptacle having downwardly and inwardly inclined inner surfaces at the ends of said chamber for supporting the card-like elements at an incline in the chamber, and a roller defining a separator resting upon the receptacle bottom and disposed transversely within said chamber and against two of said card-like elements whereby the elements on either side of the roller will be inclined in opposite directions, said roller being movable along the receptacle bottom as the card-like elements are removed from one side of the roller and replaced on the opposite side thereof for retaining said card-like elements in proper sequence and for defining an upwardly diverging gap between the elements disposed on opposite sides of the roller.

JOSEPH W. RIGNEY.
